UNITED STATES PATENT OFFICE.

CURTIS B. FLORY, OF FOREST HILLS, NEW YORK, ASSIGNOR TO FOAMITE-CHILDS CORPORATION, OF NEW YORK, N. Y., A CORPORATION OF DELAWARE.

APPARATUS FOR EXTINGUISHING TRANSFORMER AND SWITCH FIRES.

Application filed July 30, 1921. Serial No. 438,582.

In the operation of high tension power plants or stations, oil immersed transformers and switches necessary in high voltage generation and transmission work have been a frequent source or origin of fire from a number of causes. The tanks holding the oil transformers and oil switches, according to a common design, are practically air-tight and the sudden expansion of the oil or vapor in the tanks under severe and even normal operating conditions has been known to cause tank explosions with the result that the ignited oil in being projected by the fires of the explosion and in flowing from the disrupted tank, quickly spreads the fire to adjacent transformer or switch tanks. The tanks are usually provided with small vents for accommodating normal changes in internal pressure due to oil expansion; and it is a common occurrence for the oil to escape from these vents, the oil running over the outer walls of the tanks and spreading over the power plant flooring. This escaping oil is oftentimes accidentally set into combustion, with the result that the fire is communicated to the surrounding transformer and switch tanks. The tanks are also subject to disruption due to other common causes, such as line surges incident to electrical storms, excessive loads, short circuits, arcing, insulation breakdown, etc., the disruption in any of these events causing oil ignition, the escaping burning oil communicating or spreading the fires to other parts of the plant or station open to fire hazards. The provision of a system for protecting high tension power plants against spread of fire from oil immersed equipment of this nature and for extinguishing fires having their origin or inception in transformer and switch tank breakdowns is an obvious desideratum; and my present invention has for its chief object the provision of such a system.

Figure 1 is a view in elevation with parts shown in cross section of my system,

Figure 2 is a plan view thereof, and

Figure 3 is a view of a detail.

The system of my present invention comprises briefly the provision of a compartment or compartments in which the oil immersed equipment tanks are located, the tanks being isolated by the compartments from adjacent apparatus, the compartments providing means for limiting the fire area

and for limiting spread of fire due to tank disruption or breakdown and for preventing spread of overflowing oil due to normal use of the tank equipment, my system including the provision of fire extinguishing apparatus of the foam producing type arranged for delivering a mass of foam into the isolated compartment for flooding or filling the same to quickly smother the fire therein. To accomplish these ends the high tension transformer or oil tanks are mounted in a compartment 10, which may be in the form of a pit, below the grade level of the plant, the walls 11 and the flooring 12 being constructed preferably of fire proofing material such as, for example, brick or cement. Any number of tanks desired may be mounted in a compartment, it being preferred to limit the number of tanks to, for example, two tanks for each compartment. Mounted on a foundation such as 13 on the floor of the pit 10 are the two transformer tanks 14, the said transformer tanks being of the usual type constructed of heavy plate metal and made substantially air-tight, the tanks being provided with the usual insulated primary conductors 15 and the usual potted insulated secondary conductors 16. Although in the present exemplification I show the tanks 14 as oil immersed transformer tanks, it will be obvious that the tanks 14 may comprise the high tension switch tanks employed in high power plants or stations or any other oil immersed apparatus. The provision of the isolating compartment or pit 10 provides a chamber in which the overflowing oil from the tanks or the burning oil projected by tank explosion may collect without liability of spread, the fire being limited to such isolated compartment, the fire being thus prevented from spreading not only, but being localized for fire fighting purposes.

To extinguish the oil fire localized in the compartment 10 I provide a foam generating and delivery apparatus communicating with the compartment and adapted in time of fire for flooding or filling the compartment with a smothering blanket of fire extinguishing foam. To these ends I provide the foam mixing or generating chamber or head 17 located preferably adjacent the compartment 10, independent solution lines 18 and 19 being connected to the mixing head 17, the lines 18 and 19 being provided for independently conducting component solutions

from independent tanks (not shown), the solutions being conducted through the lines 18 and 19 and into the chamber 17 in opposed relation, the impinging solution jets or streams effecting solution intermixture for producing or generating a fire extinguishing foam compound. For the purpose of delivering or introducing the generated foam compound into the compartment 10 for flooding or filling the same I provide a delivery means connected to the generating head 17, the said delivery means conveniently taking the form of pipe sections 20, which may be arranged surrounding the tanks 14 and located about the walls 11 of the compartment 10, the said piping 20 being provided with a plurality of spaced perforations 21, as shown particularly in Figures 1 and 3 of the drawings, the perforations forming duct means for providing exit paths for the foam. For the purpose of extinguishing any fire presented by the ignited oil over the outer walls of the tanks 14 or on the roofs of the said tanks, I may also provide one or more foam generating sprinkler heads 22, independent solution lines 23 and 24 connecting the said sprinkler head 22 to the main solution lines 18 and 19, as shown in Figures 1 and 2 of the drawings. For the purpose of extinguishing fires present in the tanks 14 or for the purpose of covering the oil and apparatus contained in said tanks with a blanket of foam for protection in time of fire, I provide foam delivery pipe sections 25 connected to a tank or tanks 14 for foam communication with the interior of the said tank, as shown in Figure 1 of the drawings, the foam delivery pipe sections 25 being intended for connection to a foam-producing system as, for example, a foam-type engine (not shown), a valve 26 being provided in the delivery piping 25 for controlling the flow of the foam into the said tank.

While I have shown my device in the preferred form, it will be obvious that many changes and modifications may be made in the structure disclosed without departing from the spirit of the invention, defined in the following claims.

I claim:

1. A system for extinguishing oil transformer or oil switch fires, comprising a storage pit or compartment, oil transformer or switch tank means located in said compartment and isolated thereby, and apparatus for generating and delivering foam to the compartment and to the tank tops, the said apparatus comprising a mixing chamber located adjacent the compartment, independent solution supply lines connected to the mixing chamber, perforated foam delivering pipe sections arranged interiorly about the walls of the compartment and surrounding the said tanks connected to the mixing chamber, a foam generating and delivering unit located above the tank tops, and independent lines connecting the said unit to the independent solution supply lines.

2. A system for extinguishing oil transformer or switch fires, comprising a storage pit or compartment, oil transformer or switch tank means located in said compartment and isolated thereby, and a foam producing and delivering apparatus including a foam delivering means located in said compartment below the tops of the tanks therein for delivering fire extinguishing foam in time of fire for flooding the same, and additional foam delivering means located above the said compartment and above the tops of the tanks therein for supplying foam to the tank tops.

Signed at New York in the county of New York and State of New York this 29th day of July A. D. 1921.

CURTIS B. FLORY.
